ROBERT CASSADY AND JOSEPH L. CASSADY, OF HARDINGSVILLE, NEW JERSEY.

Letters Patent No. 68,841, dated September 17, 1867.

IMPROVEMENT IN CORN-PLANTERS.

The Schedule referred to in these Letters Patent and making part of the same.

TO ALL WHOM IT MAY CONCERN:

Be it known that we, ROBERT CASSADY and JOSEPH L. CASSADY, of Hardingsville, Gloucester county, New Jersey, have invented an improved Corn-Planter; and we do hereby declare the following to be a full, clear, and exact description of the same.

Our invention consists in certain devices, fully described hereafter, for depositing grains of corn in the earth.

In order to enable others skilled in the art to make and use our invention, we will now proceed to describe its construction and operation, reference being had to the accompanying drawing, which forms a part of this specification, and in which—

Figure 1 is a sectional elevation of our improved corn-planter.

Figure 2, a plan view.

Figure 3, a rear view, and

Figure 4, a plan view, showing a rake attached to the frame of the planter.

The frame A of the machine consists of an axle, A', pole B, and diagonal braces C C; and on the ends of the axle turn the two wheels D D'. To the axle A' are connected two detachable square tubes or boxes F F, in each of which slides a bar, G; and in each bar is a recess, a, and an opening, b, which is inclined downwards towards an opening, c, in the rear side of the box F. Each bar G is connected at its upper end to one end of a cross-piece, H, to the centre of which is secured one end of an arm, I; and to the lower end of the latter is jointed a lever, J, which is hung to the rear side of the axle. To the axle is hung a second lever, K', which bears at one end on the lever J, and at the other on the periphery of a ratchet-wheel, d, at the inner side of the wheel D. At the front side of each tube F is a hopper, K; and to the bottom of each hopper (which is inclined, as shown in fig. 1) is secured a strip, e, of leather, one end of which is loose, and bears against the front side of the bar F. To a standard, h, on the pole B is secured a seat, M; and to one side of the standard is hung a lever, L, the rear end of which projects beneath a notch or projection, x, on the arm I, (fig. 3,) the front end of the said lever being adjacent to the seat M. In detachable guides N N, attached to the braces C C, slide bars P P, to the lower ends of which are secured blades or scorers f f; and at the front edge of each bar are teeth, adapted to those on a segment or pinion, i, secured to a shaft, R, which turns in bearings on the frame of the machine. To the shaft R is secured an arm, m, the upper end of which is adjacent to the seat M; and on the axle A are staples n n, for a purpose described hereafter. To the axle A' is hung a detachable frame, S, from which project two arms t t; and at the lower end of each of the latter is a plate or blade, w. To the frame S is secured an arm, V, the front end of which is adjacent to the seat M.

As the machine is drawn forward, furrows will be made in the earth by the blades f f, and a reciprocating vertical motion will be imparted to the bars G G by the ratchet-wheel d, acting through the medium of the levers K', the arm I, and cross-piece H. When the bars are elevated the grains of corn in the hopper will pass into each of the recesses a, and on the downward movement of the bar will be carried below the flexible strip e. As the bar again rises the end of the strip e will be introduced between the side of the bar and the grains of corn in the recess a, and will withdraw the grains from the recess, and will discharge them into the opening b as it is brought opposite the strip. The grains pass through the openings b and c into the furrow made by the plate f, and are then covered with earth, which is thrown over the furrow by the plate w. When the machine is to be turned, the attendant throws forward the arm m, and depresses the arm V, and thus raises the scorers f and plates w from the ground. He then depresses the forward end of the arm L, so as to elevate the arm I with the cross-piece M and bars G. The lever J is thus moved out of contact with the lever K', and the further passage of grain from the hopper is prevented.

When a horse-rake is required, the boxes F F, frame S, and guides N N may be detached from the frame of the machine, and a bar, X, to which are connected a number of bent rods or teeth x, may be secured to the staples n.

We claim as our invention, and desire to secure by Letters Patent—

1. The boxes F F, hoppers K K, bars G G, cross-piece H, and arm I, in combination with the ratchet-

wheel *d* and the levers *J K'*, or their equivalents, the whole being constructed and operating substantially as and for the purpose described.

2. The frame *S*, with its arms *t* and plates *w*, hung to the frame *A*, substantially as specified.
3. The adjustable bars *P P* and their plates *f*, in combination with the shaft *R* and its pinions *i*, or their equivalents, the whole being arranged on the frame *A*, substantially as and for the purpose set forth.

In testimony whereof we have signed our names to this specification in the presence of two subscribing witnesses.

ROBERT CASSADY,
JOSEPH L. CASSADY.
